UNITED STATES PATENT OFFICE.

MARY A. ENGEL, OF CARRICK, PENNSYLVANIA.

BASKET.

No. 882,935.

Specification of Letters Patent. Patented March 24, 1908.

Application filed January 5, 1907. Serial No. 350,877.

To all whom it may concern:

Be it known that I, MARY A. ENGEL, citizen of the United States of America, residing at Carrick, in the county of Allegheny and State of Pennsylvania, have invented certain new and useful Improvements in Baskets, of which the following is a specification, reference being had therein to the accompanying drawing.

10 The invention relates to certain new and useful improvements in clothes baskets, and the invention has for its object the provision of novel means in connection with a clothes basket for housing clothes pins commonly used for suspending clothes upon a clothes line.

My invention aims to provide a basket having compartments formed therein containing clothes pin bags which are detachably connected to the basket, whereby they may be removed and washed.

The detail construction of my improved basket will be presently described and then specifically pointed out in the claims.

25 Referring to the drawing forming part of this specification, like numerals of reference designate corresponding parts throughout the several views, in which:

Figure 1 is a side elevation of a basket constructed in accordance with the invention, Fig. 2 is a longitudinal sectional view of the same, Fig. 3 is a plan of the basket, Fig. 4 is a detail sectional view illustrating the manner of securing a bag in its basket compartment.

In the accompanying drawing, I have illustrated a basket 1 having side walls 2 and flaring end walls 3, said end walls being provided with suitable handles 4. At the 40 ends of the basket, I form vertically disposed partitions 5, said partitions forming end compartments 6 in which bags 7 are mounted and a central rectangular compartment adapted to contain articles of clothing, said

bags being constructed of a suitable durable 45 fabric and provided with draw strings, 8, whereby the bags can be closed. The bags 7 are provided with clasp members 9 adapted to engage clasp members 10, suitably arranged within the compartments 6, said 50 clasp members being similar to an ordinary glove clasp. The bags 7 of my improved basket are adapted to contain clothes pins and prevent the pins from being lost or scattered among the clothes contained within 55 the basket. By placing the pins in special compartments within the basket the trouble of carrying the pins separately is obviated, and the pins can always be found when needed.

60 What I claim and desire to secure by Letters Patent, is:—

In combination a clothes basket having flaring ends, a vertically disposed partition arranged therein adjacent to each end thereof and forming thereby in connection with the ends of the basket a pair of pockets which gradually increase in width upwardly and further providing a rectangular compartment of a height of the basket, a flexible 65 receptacle mounted in each of said pockets and formed with a mouth, a draw string connected to each of the receptacles and adapted to close the mouth thereof, a fastening member carried by each of said receptacles, and a fastening member carried by each of said partitions, said fastening members carried by the partitions adapted to interengage with the fastening members carried by the receptacles, thereby securing 70 75 80 the receptacles within the pockets.

In testimony whereof I affix my signature in the presence of two witnesses.

MARY A. ENGEL.
